(57) **CLAIM**

The ornamental design for a fluid atomization device, as shown and described.

DESCRIPTION

FIG. 1 is a top-front-left perspective view of a fluid atomization device showing my new design;

FIG. 2 is a bottom-rear-right perspective view thereof;

FIG. 3 is a front elevational view thereof;

FIG. 4 is a rear elevational view thereof;

FIG. 5 is a left-side elevational view thereof;

FIG. 6 is right-side elevational view thereof;

FIG. 7 is an enlarged top plan view thereof;

FIG. 8 is an enlarged bottom plan view thereof;

FIG. 9 is a detail view of area 9 in FIG. 1;

FIG. 10 is a detail view of area 10 in FIG. 2; and,

FIG. 11 is a left-side elevational view of a second embodiment of a fluid atomization device shown broken away for indeterminate length, that being the only difference from the embodiment shown in FIG. 1 through 10.

The broken line showing an internal volume of the nozzle body and apertures leading thereto in FIGS. 1, 2, 3, 4, 7, 8, 9, and 10; the supply line fittings in FIGS. 1, 2, 3, 4, 5, 6, 7, 8, and 11; and the exemplary couplers in FIG. 1 through 11 is included for the purpose of illustrating environmental structure and forms no part of the claimed design.

Additionally, the fluid atomization device is shown with symbolic breaks in its length. The appearance of any portion of the article between the break lines forms no part of the claimed design.
